The ornamental design for a foot wedge for squatting exercises, as shown and described.

DESCRIPTION

FIG. 1 is a perspective view of a foot wedge for squatting exercises illustrating my new design;
FIG. 2 is a side elevational view thereof, the opposite side being a mirror image thereof;
FIG. 3 is a top plan view thereof;
FIG. 4 is a front elevational view thereof;
FIG. 5 is a rear elevational view thereof; and,
FIG. 6 is a bottom view thereof.
